FIG. 3

Inventor

JOSEPH KLANSNIC

By *Henry L. Reynolds*,
Attorney

UNITED STATES PATENT OFFICE.

JOSEPH KLANSNIC, OF BLACK DIAMOND, WASHINGTON.

SAFETY-STOP FOR MINE-CARS.

1,297,575.

Specification of Letters Patent. Patented Mar. 18, 1919.

Application filed January 31, 1918. Serial No. 214,618.

To all whom it may concern:

Be it known that I, JOSEPH KLANSNIC, a citizen of the United States, and resident of the town of Black Diamond, county of King, and State of Washington, have invented certain new and useful Improvements in Safety-Stops for Mine-Cars, of which the following is a specification.

My invention relates to a safety stop attachment for mine cars and consists of certain improvements over a device of the same character shown in my previous Patent No. 1,219,748, dated March 20, 1917.

The object of my present invention is to improve upon the construction of the car therein shown, and particularly along the line of providing means by which the parts may be locked in the position assumed when the car body is raised, and also in the providing of mechanism whereby the swinging of the levers upon which the wheels are journaled, cannot take place in the opposite direction from that which is intended. Other objects will be disclosed from a study of the specification in this case and the features which I claim to be novel will be defined by the claims terminating said specification.

In the accompanying drawings I have shown my device embodied in the form of construction which I now prefer.

Figure 1 is a side elevation of a car showing a portion of one side and the central partitions broken away, in order to better show the operating mechanisms.

Fig. 2 is a plan view of my car showing a portion of the body broken away in order to better show the mechanism.

Fig. 3 is an end elevation of a car having my improvement thereon, a portion of one end of the body being broken away to show parts behind the same.

In the construction of cars shown in my previous patent above referred to, no provision was made to prevent the car from dropping down upon the rails when the heavy strain, due to hauling up an incline, is removed. It would, therefore, be impossible to operate said cars except on inclines where the backward strain upon the haulage rope would be sufficient to maintain the body of the car raised. Should the car, as shown in said patent, run upon a level stretch it would immediately drop the car body upon the track.

Furthermore, no provision was made to

prevent swinging the levers to such a point where the levers, upon which the car wheels are journaled, would swing backward beyond a perpendicular position and would thus permit the car body to settle forward, or in the opposite direction to that intended, until it rested upon the track structure.

In my present invention the structure of the car body is, in the main, similar to that shown in said patent. 1 represents the body of the car and 2 the longitudinal beams which are below the floor. These beams, as in said patent, are provided with spurs or dogs 20 which project downward a sufficient distance to make certain their engagement with the ties or with other parts of the track structure in such manner as to stop the car and hold it, even if it be upon a considerable grade.

In some cases a timber is employed extending lengthwise of the track, which timber would be placed so as to be engaged by the spurs 20. These spurs are preferably secured to a plate 21 which is secured to the under side of the beam 2. They are preferably made detachable so they may be renewed in case one becomes broken or pulled out.

Car axles 3 are journaled upon the car body in accordance with the construction shown in said patent. Lever arms 4 are secured to these axles or shafts 3 at opposite ends and the track wheels 9 are journaled upon the swinging ends of these levers. 90 Lever arms 5 are also secured to these shafts, one upon each shaft. These latter arms, instead of being placed at the outside of the car body, one at each side thereof, as was done in said patent, are placed at the center, 95 one for each shaft 3.

Each of the axles is provided with its lever 5, and these are connected by a link 50, which link is also provided with means whereby the haulage connection may be made therewith. A shield or casing 11, shaped to accommodate the wheels when the car body drops down, is provided over each wheel, this being shaped so as to accommodate the wheels and the lever arms upon 105 which the wheels are mounted.

The main haulage connection is through a member 60 which is connected with a draft bar 6 secured to the frame of the car. The cable by which the car is pulled, 110 is connected with the eye 62 to which the member 60 is secured and to which also is

secured a like member 61, this extending to a connection with the forward end of the link 50.

To accommodate the levers 5, and the parts connected therewith, as 50 and 61, a narrow compartment running lengthwise the car is formed by the two walls 12. This compartment may extend throughout the length of the car and ordinarily would do so, but might be cut short at the end opposite the haulage connection. This compartment should preferably be covered on top and be open at the end where the cable 61 enters.

15 It is evident that the strain upon the haulage cable communicated through the connecting member 61, will act upon the longer lever 5, to swing the shorter lever 4, upon which the wheels are mounted, downward and backward, thus raising and maintaining the car body in elevated position so long as this strain is continued. However, when this strain is released, the relative angular positions of the lever arms 4, as referred to a perpendicular, will cause the car body to drop backward.

The strain communicated through this connecting member 61 is found to not be sufficient to maintain the car body raised when the car is on a level track, or a track with a slight grade. It is, however, desirable to be able to operate these cars upon such level sections. I, therefore, provide a locking link 8, which is pivoted to a bar 80 secured to one end of the car body, which link 8 is provided, at its freely swinging end, with a hook which engages the forward end of the link 50, or with any other suitable member which is connected with the levers 5. When so engaged, the car body will be maintained in raised position, even if the strain is entirely removed from the connecting member 61.

45 As herein shown, I have provided a recess at 70 in the outer sides of the longitudinal beams 2 and in the metal plate 21, which recess accommodates the lever arms 4 upon which the wheels are journaled. The shoulder 7 at the rear end of this recess, is so placed that it will engage the lever arm 4 and prevent it from swinging backward farther than is desired.

This stop may, of course, be provided by other means, but the one described I have found convenient and satisfactory. By the use of a stop located in this manner it is impossible for the levers to swing too far in the backward direction. Should the wheel carrying levers swing forward to such point that the car body will settle upon the track-way, the car body can be automatically raised by pulling upon the haulage lines, as it could not if the levers were to swing backward or in the opposite direction.

65 It is believed that the operation of this

device is evident and that further detail description thereof is unnecessary.

What I claim as my invention is:

1. The combination with a car body having a narrow compartment extending centrally lengthwise thereof, axles journaled upon the body, arms secured to the ends of the axles, wheels mounted on said arms, arms secured to the axles and extending upward in said central compartment, a haulage connection directly with the car and a supplementary haulage connection with said latter arms. 70

2. The combination with a car body of axles journaled thereon, lever arms secured to said axles, car wheels journaled on said lever arms, controlling arms centrally secured to the axles and extending upward, longitudinal vertical partitions forming a narrow compartment inclosing said controlling arms, a member connecting said controlling arms with the car haulage connection, and means for locking said arms in position to maintain the car body in raised position. 80

3. The combination with a car body of axles journaled thereon, lever arms secured to said axles, car wheels journaled on said lever arms, controlling arms centrally secured to the axles and extending upward, longitudinal vertical partitions forming a narrow compartment inclosing said controlling arms, a member connecting said controlling arms with the car haulage connection, a dog or hooked link pivoted in said central compartment and adapted to engage 90 the controlling arms to hold the car body in raised position. 95

4. In a car, in combination, a car body having a floor sill at each side, axles journaled above said sills, arms fixed to said axles and extending downwardly, the sills being recessed to accommodate said arms and permit their swinging to a horizontal position in one direction, one end wall of said recesses being located to act as a stop for the arms to prevent their swinging beyond a vertical in the other direction, and a car haulage means acting through said axles to swing said arms toward a vertical position. 105

5. In a car, in combination, a body having a centrally placed longitudinally extending compartment, axles journaled on the body and extending through the bottom of said compartment, arms secured to the ends of said axles, wheels journaled on said arms, a lever arm secured centrally to each axle and extending upward in said central compartment, and a car haulage means comprising a member extending into said compartment and connected with said lever arms. 115

6. A car for operation on inclines comprising a body having means on its lower side for positive engagement with the track structure when lowered thereon, axles journaled on the body, arms fixed on the ends of 120

said axles, wheels journaled on said arms, a lever secured centrally on each axle and extending upwardly, means connecting said levers of different axles to secure uniformity 5 of position thereof, the car body having a longitudinally extending compartment inclosing said levers, and means connecting

said levers with the haulage means to maintain the wheels in lowered position, and stops limiting the swing of said levers. 10

Signed at Black Diamond, Washington, this 11th day of December, 1917.

JOSEPH KLANSNIC.
